UNITED STATES PATENT OFFICE.

WILLIAM P. PITTS, OF INDEPENDENCE, MISSOURI, ASSIGNOR TO IRVING-PITT MFG. CO., OF KANSAS CITY, MISSOURI.

LOOSE-LEAF BOOK.

No. 876,395.

Specification of Letters Patent.

Patented Jan. 14, 1908.

Application filed November 5, 1906. Serial No. 342,009.

To all whom it may concern:

Be it known that I, WILLIAM P. PITTS, a citizen of the United States, residing at Independence, in the county of Jackson and 5 State of Missouri, have invented certain new and useful Improvements in Loose-Leaf Books, of which the following is a specification.

This invention relates to loose-leaf books; 10 and is an improvement over Patent #778,070.

The present invention consists of means operated at the back of the book for rocking the hook-carrying members of said book, so that the hooks may be readily opened 15 for the insertion or removal of loose-leaves without grasping said hooks.

The invention further consists of means for securing the parts to the back of the book.

Referring now to the accompanying drawing which illustrates the invention, Figure 1 represents a loose-leaf book provided with my improvement. Fig. 2 is an enlarged 20 central section of the same, on line II-II of Fig. 1. Fig. 3 is a plan view of the back-plate provided with means for rocking the hook-carrying members. Fig. 4 is a trans- 25 verse section on line IV-IV of Fig. 1.

1 designates the cover of the book.

2 designates a spring-plate.

3 designates a plurality of hook-carrying members, rockingly mounted in the spring-plate.

4 designates the hooks which are carried 30 by members 3, for the reception of loose-leaves.

5 designates a retaining plate embracing the edges of the spring-plate.

All of the above parts are constructed and 40 arranged substantially like those shown in the patent above referred to, with the exception that the hook-carrying members consist of four pieces in the present instance, instead of but two as shown in the patent.

45 6 designates the back-plate, which is secured to cover 1 by a piece of fabric 6^a. Said plate extends the length of the spring-plate 2, and is provided at its ends with fingers 7, which clasp said spring-plate and 50 reliably hold it in position.

8 designates a pair of resilient members stamped from the back-plate and provided 55 with their free ends with projections 9, which

extend through openings 10 in the back-plate, openings 11 in the fabric, and openings 12 in the spring-plate, so that they may bear against the undersides of the hook-carrying members 3.

With the above construction it is obvious that the hooks may be simultaneously 60 opened by either pressing downwardly upon the retaining plate 5, or pressing upwardly upon the free ends of members 8 until projections 9 force the abutting edges of the hook-carrying members above a horizontal 65 plane, after which spring-plate 2 will continue to force said edges upwardly until they abut against the underside of the retaining plate 5. The upward movement will open the hooks to the dotted position shown in 70 Fig. 4.

Members 8 are arranged wholly within the length of the back-plate, so that their free ends will not project beyond the latter and cause annoyance by catching in the wearer's 75 garment.

The back-plate 6 may be dispensed with by stamping members 8 from the spring-plate, but I prefer to employ said back-plate because it reinforces the back of the book 80 and affords convenient means for attaching and detaching the other members to said book.

When only two hook-carrying members are employed, as shown in the patent, one of 85 the resilient members 8 may be dispensed with.

Having thus described my invention, what I claim is:

1. The combination with a loose-leaf book 90 having a plurality of rockingly mounted hook-carrying members, of means operated by pressure on the back of the book and adapted to press against and rock said members to open the hooks.

2. The combination with a loose-leaf book having a plurality of rockingly mounted hook-carrying members, of means operated by pressure on the back of the book and provided with projections adapted to press 100 against and rock said members to open the hooks.

3. The combination with a loose-leaf book having a plurality of rockingly mounted hook-carrying members, of a back-plate secured to the back of said book and provided 105

with means operated by pressure on the back of the book and adapted to press against and rock said members to open the hooks.

4. The combination with a loose-leaf book
5 having a plurality of hook-carrying members, and a spring-plate in which said members are rockingly mounted; said plate having openings extending therethrough, of means provided with projections extending

through said openings and adapted to press against and rock said members to open the hooks.

In testimony whereof I affix my signature, in the presence of two witnesses.

WILLIAM P. PITTS.
